UNITED STATES PATENT OFFICE.

DOMENICO SUMMA, OF NEW YORK, N. Y.

WATCH-PROTECTING FOB-CHAIN.

SPECIFICATION forming part of Letters Patent No. 741,564, dated October 13, 1903.

Application filed June 4, 1903. Serial No. 160,049. (No model.)

To all whom it may concern:

Be it known that I, DOMENICO SUMMA, a citizen of the United States, and a resident of the city of New York, borough of Manhattan, in the county and State of New York, have invented a new and Improved Watch-Protecting Fob-Chain, of which the following is a full, clear, and exact description.

My invention relates to watch-protecting fob-chains, and is an improvement upon my former invention covered by Letters Patent No. 718,399, dated January 13, 1903, for a watch-protector.

Reference is to be had to the accompanying drawings, forming a part of this specification, in which similar characters of reference indicate corresponding parts in all the figures.

Figure 1 is a perspective view showing my invention ready for use. Fig. 2 is an enlarged section upon the line 2 2 of Fig. 1 looking in the direction of the arrow. Fig. 3 is a fragmentary elevation on the line 3 3 in Fig. 2 looking in the direction of the arrow. Fig. 4 is an enlarged fragmentary perspective view of the right-hand portion of Fig. 1, showing one of the pivotal mountings for the plate 12. Fig. 5 is a fragmentary view of the lever 12.

A plate 1 is bent upon itself, being thereby provided with a disk-like portion 2. The plate is so placed upon a pocket that the disk-like portion is upon the outside and the plate 1 is upon the inside of the pocket. A ring 3 is provided and may be used for the purpose of engaging a chain. Holes 4 5 in the plate 1 are engaged by chains 6 7, as indicated in Fig. 1. A hole 8 in the disk-like portion 2 may be used for connecting a chain or other pendent member with the device, this pendent member being upon the outside of the pocket while in use. The ring 3 is mounted within a bearing 9 and may not be used unless desired. It may serve as an auxiliary device and is used in the manner described in my Letters Patent above mentioned.

Supported within bearings 10 11 in the plate 1 is a plate 12, provided with ears 13 14. This plate 12 is provided with a projecting portion 15, having teeth 16, this projecting portion constituting a claw member. The claw member and the plate 12 are integrally connected together and form a sort of an L-shaped lever, as may be seen from Figs. 2 and 4. The

plate 1 is provided with bearings 17 18, which engage ears 19 20 in the plate 12, thus enabling the plate 12 to be rocked relatively to the plate 1. A button 20^a is mounted upon a stem 21, which passes through a slot 22 in the plate 1. Upon the inside of the plate 1 is another button 19^a, which is also rigidly mounted upon the stem 21. The two buttons, with their connecting-stem, constitute a clasp member which may be moved relatively to the slot 22 and plate 1.

My invention is used as follows: The plate 1 is slipped into the pocket or behind a belt, as the case may be, the disk-like portion 2 being upon the outside and exposed to view. The ring 3 is an auxiliary member having no immediate relation to my present invention. The chains 6 7 are secured one to the clothing and the other to a watch, chatelaine-bag, purse, or other similar article to be protected. These chains have, generally speaking, the same office as the individual members of a two-part watch-chain. At the moment when the device is placed in position the plate 12 is raised outwardly at a right angle, so that the teeth 16 do not engage the clothing. The plate 1 being in position, the plate 12 is forced downwardly and into the position indicated in Fig. 2, so that the claw portion 15 assumes a right angle with the plate 1 and the teeth 16 are caused to grip the cloth. The clasp members, consisting of the buttons 19^a 20^a, connected by the stem 21, are next slipped downward, as indicated by full lines in Fig. 2 and by dotted lines in Fig. 3, so as to hold the plate 12 rigidly in position relatively to the plate 1. The button 19^a now occupies the position indicated by dotted lines in Fig. 3, so that the plate 12 is unable to move downwardly or to the right from the view-point of Fig. 3. The lower end 12^a of the plate 12 is too long to pass through the aperture 12^b in the plate 1, so that the plate 12 is unable to move inward, as indicated in Fig. 2. If now any person should seize the watch or other article to be protected or pull heavily upon one of the chains—say the chain 7—the watch-protector cannot be removed from the clothing, for the reason that the teeth 16 cannot be disengaged.

The device may be used to advantage by either ladies or gentlemen and may be em-

ployed to protect such articles as keys, scissors, and the like, as well as articles to be worn for ornamentation.

Having thus described my invention, I 5 claim as new and desire to secure by Letters Patent—

- 10 1. A watch-protecting fob-chain, comprising a plate provided with chains, a lever pivotally mounted upon said plate and normally free to rock relatively thereto, said lever being provided with a claw, and a clasp slidably mounted upon said lever and movable relatively to said plate for the purpose of locking said lever thereto.
- 15 2. A watch-protecting fob-chain, comprising a plate doubled upon itself for the purpose of clasping the edge of a pocket, and provided with means for engaging a chain, a lever pivotally mounted upon said plate and

provided with a claw and with a slot, and a 20 clasping member slidably mounted upon said lever and provided with a portion engaging said slot for the purpose of securing said lever and said plate rigidly together.

3. A watch-protecting fob-chain, comprising a plate provided with means for engaging a chain, a lever pivotally mounted upon said plate and provided with a claw, and a 25 clasping member mounted upon said lever and free to engage said plate for the purpose 30 of locking said lever relatively to said plate.

In testimony whereof I have signed my name to this specification in the presence of two subscribing witnesses.

DOMENICO SUMMA.
